UNITED STATES PATENT OFFICE.

IRVIN R. FENNER AND WILLIAM D. FENNER, OF SAN FRANCISCO, CALIFORNIA.

ANKLE-JOINT FOR ARTIFICIAL LIMBS.

SPECIFICATION forming part of Letters Patent No. 667,511, dated February 5, 1901.

Application filed October 22, 1900. Serial No. 33,985. (No model.)

To all whom it may concern:

Be it known that we, IRVIN R. FENNER and WILLIAM D. FENNER, citizens of the United States, residing at San Francisco, in the county of San Francisco and State of California, have invented certain new and useful Improvements in Ankle-Joints for Artificial Limbs, of which the following is a specification.

Our invention relates to improvements in 10 ankle-joints for artificial limbs, one object of our invention being to provide a joint which shall permit movement of the foot with very little friction and which shall at the same time be very strong and equalize the strain on 15 both sides of the foot, so as to cause the foot to rest always squarely upon the floor, and one, moreover, in which the extent of movement of the joint shall not be unduly limited, but which permits the foot to bend as far as 20 needed.

A further object of our invention is to provide a device of this character which can be attached and removed with very little trouble.

Our invention therefore resides in the novel 25 construction, combination, and arrangement of parts for the above ends hereinafter fully specified, and particularly pointed out in the claims.

In the accompanying drawings, Figure 1 is 30 a longitudinal vertical section of an artificial shin and foot attached by means of our improved ankle-joint. Fig. 2 is a transverse section of the same; and Fig. 3 is a longitudinal section taken on the line A A of Fig. 2, 35 showing the ankle-joint detached.

Referring to the drawings, 1 represents the 40 shin portion of an artificial limb, and 2 the foot portion thereof. Upon a specially-prepared groove 3, sunk into the upper portion 40 of the foot, rests a semicylindrical plate or lower member 4, said plate having a groove 5 near each end to receive balls 6, said balls being stopped at the end of said grooves by means of pins 7 in the plate 4. Upon these 45 two series of balls rolls the upper member 8 of the joint, having a general cylindrical form and having at its ends the annular grooves 9 to receive said series of balls 6. Said upper member or cylinder 8 is secured to the 50 shin portion of the leg by means of rods 10, which are passed through said upper member

and also through the solid portion 11 of the shin and are anchored thereto by means of nuts 12, said nuts permitting the joint to be readily secured to limbs of different sizes. 55

The lower member or plate 4 of the joint is secured to the foot 2 by means of a rod 13, which passes through an aperture 14 in said lower member and also through an elongated or slotted aperture 15 in the cylinder 8 and 60 is secured to a cylindrical head 16, rotating in said upper member. The pin 17, driven through the rod 13, secures the plate 4 thereto. The rod 13 passes through the foot and is anchored thereto by means of a nut 18. It will 65 be seen that with this construction all that is necessary in order to remove the foot from the shin portion is to unscrew the nut 18 and withdraw the foot from the rod 13 and the ankle-joint. The ankle-joint may similarly 70 be removed from the shin portion by unscrewing the nuts 12. When the joint is removed, the several parts thereof will still be connected, and there is no possibility of the balls falling out or being lost when the limb is 75 taken apart. At the same time the joint is a very strong one, owing to the fact that the upper member has a double bearing on the lower member—viz., the ball-bearing—and the cylindrical head 16 rotating within the cylindrical socket of the upper member. The ball-bearings at the extreme ends of the joint 80 tend to equalize the strain on both sides of the foot. The greatest pressure is evidently taken up by the ball-bearings, said bearings 85 sustaining the direct weight of the leg and body upon the foot.

19 indicates rods which serve the purpose of returning the foot to its normal or horizontal position; but these rods form no part of our 90 present invention.

We claim—

1. In an ankle-joint for an artificial limb, the combination of the upper member, secured to the shin portion, the lower member, said upper and lower members being correspondingly grooved to contain balls, the balls therein, and the rod for connecting the lower member to the foot, said rod having a cylindrical head rotating within the upper member, substantially as described. 95
2. In an ankle-joint for an artificial limb, 100

the combination with the shin portion and the foot portion of the limb, of upper and lower members having corresponding grooves at their ends, balls in said grooves, end stops for said balls, rods passed through the upper member, nuts for securing said rods to the shin portion, a rod passed through the lower member, a nut for attaching said rod to the foot portion, and a cylindrical head rotating ⁵ within the upper member, to which head said

latter rod is attached, substantially as described.

In witness whereof we have hereunto set our hands in the presence of two subscribing witnesses.

I. R. FENNER.
W. D. FENNER.
